METHOD OF AND MACHINE FOR EFFECTING
COMBINED FASTENING AND SEAM COV-
ERING STITCHESErnst Bucher, Zurich, Switzerland, assignor to
the firm Mauser-Werke A.-G., Oberndorf-on-
the-Neckar, Wurttemberg, GermanyApplication August 31, 1933, Serial No. 687,686
In Switzerland September 10, 1932

9 Claims. (Cl. 112—122)

This invention relates to methods of and machines for effecting combined fastening and seam covering stitches for sewing two pieces of fabric together and simultaneously covering the seam 5 in such manner that the edges of both pieces of fabric are trimmed during the seaming operation and so fastened to each other that a suture with a raised marginal portion as little as possible is obtained and said portion is sewed down 10 flat by means of covering stitching.

It is known to perform such seams in two working incidences in two different machines. It is also known to effect such seams in one working incidence in one and the same machine. All 15 the known modes of effecting seams of this kind failed however to solve the problem involved in an entirely satisfactory manner as required for practical purposes, the cost of the work being too great, for example when it is performed in 20 two different working incidences. On the other hand, the work is rendered too expensive when, due to the particular nature of the fastening seam, it is required to apply lapping threads on 25 the upper side of the suture, thus necessitating a considerable amount of additional thread material. Or the use of lapping threads may result 30 in rendering the seam on the outer side of garments too perspicuous (for example in knitted upper garments and so forth), or because of the 35 suture not being sufficiently flat as during effecting the fastening seam too voluminous a lap was formed, or else due to the sewing needles being positioned too far apart, the performance of stitches in the form of pointed arches or similar ornamental stitching is rendered impossible and so forth.

The object of the present invention is to obviate all these drawbacks. The method according to the invention consists in fastening the pieces 40 of fabric to be sewed together by means of one of the needles required for effecting a plural needle seam in such manner that one of the margins is pierced only at its extreme edge, whereas the other fabric margin is pierced behind the edge. 45 This mode of stitching is obtained by folding the one fabric margin down at a certain angle inwardly in the direction in which the respective piece of fabric is brought on, and the margin of the other piece of fabric is passed under the 50 first fabric margin so as to extend in the same direction and thus in the direction opposite to that in which the second piece of fabric is brought on.

The advantage obtained with a suture according to this invention consists in permitting of

trimming the fabric edges during the stitching operation more closely to the underside of the fabric than was hitherto possible with sutures serving for the same purpose. Thus, practically no projecting edges remain untrimmed and the 5 small marginal portion left is completely sewn in or covered in perfectly flat manner by the sewing needles provided for covering this projecting margin, without impairing the strength of the suture as compared to one whereby both 10 pieces of fabric have been pierced substantially behind their edges.

Still another advantage of the suture according to this invention resides in both pieces of fabric being fastened together directly by a seam, 15 without the use of lap threads on the upper side of the seam or impairing the strength thereof in the least. On the other hand lap threads may be sewn in the seam, when required for ornamental purposes. Furthermore, due to its particular nature, the suture according to the invention can be effected in different ways, namely that the needle serving for fastening the two 20 fabric margins together either operates as the middle needle of three or more parallel needles 25 and is situated in the same plane with the other needles, or that this needle operates in detached leading position from the other needles in which case the working incidence of fastening the pieces 30 of fabric together takes place somewhat earlier than that of covering the seam. The difference 35 between the two arrangements for performing the combined seams consists in that in the former case but a single suture is effected, whereas in the latter case two independent stitchings are effected, namely a fastening stitching and a seam covering stitching.

In contradistinction to the most part of the hitherto known seam covering stitching effected in a single working incidence the novel suture 40 has the further great advantage inherent thereto that in sewing tubular goods the suture is effected while the outside of the tube is turned outwardly, so that turning the tube inside out after it has left the sewing machine is no longer necessary. 45 Moreover, the novel suture is distinguished from the hitherto most used seam covering stitching effected in two separate working incidences by a pleasing aspect, the suture, due to the fabric margins being fastened together in oblique relationship, being considerably flatter. Owing to the fact that the novel suture offers substantially the same texture as the usual covering seams the manufacturer who is striving to keep his machine 50 plant up to date, but could not furnish goods 55

provided with two kinds of seams of entirely different texture, is enabled to carry out his rationalizing tendencies commensurate with his financial capacity. This possibility is not existing 5 with the hitherto known compound trimming and seam covering machines requiring lap threads to be applied to the upper side of the fabric.

The trimming of the fabric edges is effected 10 during one and the same working incidence by means of a cutting mechanism the construction of which depends on the type of machine selected for effecting the suture (cylinder sewing machine, or machines adapted for feeding in the upward or downward direction of the arm respectively, or else flat sewing machines).

In the accompanying drawings the invention is 15 illustratively exemplified in several modified forms in which

20 Fig. 1 is a perspective view of a sewing machine used for carrying out the invention;

Fig. 2 illustrates in a sectional view the manner of inserting the two pieces of fabric in the feed channel of the needle plate.

25 Fig. 3 illustrates in a cross section on the line III—III in Fig. 5 the sewing needles together with the manner in which the two pieces of fabric are folded at a certain angle and the knife in its position assumed just before trimming the fabric 30 edge;

Fig. 3a shows a cross section similar to Fig. 3 but with the knife in a lowered position after the severing of the fabric edge.

35 Fig. 3b shows a longitudinal section of the cutting mechanism in conjunction with the sewing needles, the knife being mounted on the feed carrier by means of a holder;

Fig. 3c is a top view of the thread gripping members and the knife;

40 Fig. 4 shows in a cross section on the line IV—IV in Fig. 5 the sewing needles, the trimmed fabric edge and the manner in which the left piece of fabric is pierced at the very edge and the right piece of fabric pierced substantially behind the edge, the fastening seam being in its initial stage 45 and the looper on the verge to catch the loop formed in the needle thread;

Fig. 5 shows in a plan view the needle plate inclusive of the fabric feed channel and the knife;

50 Fig. 6 illustrates in a section on the line VI—VI in Fig. 5 the manner in which the left and right fabric margins are further folded over and pierced by the needles, and the looper catches the needle thread loop of the left hand needle, the seam 55 covering stitching having just begun;

Fig. 7 shows a longitudinal section of the fastening seam on the line VII—VII of the suture in Fig. 4 indicating the left piece of fabric to be pierced at its extreme edge and the right piece of fabric pierced substantially behind the edge;

60 Fig. 8 depicts the fastening seam and the seam covering stitching as seen from the upper side (to the left in this figure) and as seen from the underside of the fabric (to the right in this figure);

65 Fig. 9 illustrates in a section through the needle plate the manner in which the two pieces of fabric are inserted in the feed channel of this plate in conjunction with a modified adjustable cutting mechanism which in distinction from the one shown in Fig. 3 severs both fabric edges in the horizontal direction;

70 Fig. 10 shows a section on the line X—X in Fig. 10a with the marginal portions of the two pieces of fabric folded at corresponding angles;

Fig. 10a is a plan view of the needle plate showing the feed device, the fabric feed channel and the knife;

Fig. 11 shows a cross section on the line XI—XI in Fig. 10a indicating both pieces of fabric to be 5 each pierced one time fully behind the edge by the left and right needles respectively and the upper piece pierced at the very edge, and the lower piece pierced fully behind the edge by the middle needle, with the overlapping fabric margin 10 extending horizontally and the looper catching the thread loop formed by the left needle;

Fig. 12 shows a longitudinal section through the suture on the line XII—XII in Fig. 11 at the middle needle indicating the left piece of fabric 15 to be pierced at its very edge and the right piece pierced fully behind the edge;

Fig. 13 depicts the suture as seen from the upper and lower sides of the fabric to the left and to the right in this figure respectively;

20 Fig. 14 shows a longitudinal section of the cutting mechanism inclusive of the looper and needle;

Fig. 15 shows a plan view of the cutting mechanism with the looper and needle in their respective positions, and

25 Fig. 16 is a perspective view of the adjustable cutting mechanism, comprising means of varying the throw of the knife, inclusive of the drive for the looper shaft.

The Figs. 1 to 8 illustrate the manner in which a suture consisting of a fastening stitching and a seam covering stitching is effected by means of a set of needles one of which is leading the others.

30 The Figs. 9 to 16 illustrate the manner in which a plural needle seam covering stitching or an over-cast seam is performed, all the needles being arranged parallel.

Fig. 1 shows by way of example, a cylinder 40 sewing machine which is adapted for carrying out the method according to the invention and in which the fabric is fed upwardly on the arm. The machine comprises a needle bar 1 to the lower end of which the needles 2 are fastened. 45 The needle bar is imparted its vertical reciprocating movement by means of a needle actuating lever 3 and a cam mechanism 4 arranged on the main drive shaft 5. The main drive shaft 5 is driven by means of a driving disc 6. The looper 50 shaft 16 (Figs. 3b and 16) is imparted its axial and radial movements, and the feed carrier its vertical reciprocating as well as advancing and retracting movements in a known manner (not shown) from the main shaft 5.

55 The manner in which the two pieces of fabric 7 and 8 are brought on for effecting the fastening and seam covering stitching is illustrated in Fig. 2. In this figure it is evident that both marginal portions of the two pieces of fabric are 60 directed vertically downwardly in a feed channel 9. Fig. 5 shows the exact shape of the feed channel and the needle plate 10.

Before effecting the fastening seam 11, the margins of the pieces of fabric are trimmed by means 65 of a cutting mechanism as a cutting knife 12 (Figs. 3, 3a, 3b, 3c, and 5). The knife 12 may be mounted on the feed dog 13 by means of a connecting device 14 so as to be adjustable to height, thus transversely to the suture, as well as in the 70 direction of the same. As is well known, the feed dog 13 performs a horizontal and a vertical reciprocation. The knife 12 shares in these movements, as it is screwed to the carrier of the feed dog and engages in a slot 10a of the needle plate 75

10 (Fig. 5). With this arrangement the knife 12 is adapted to cut from above to below and vice versa, the cutting edge of the knife being correspondingly shaped.

5 In the Figs. 9, 14, 15, and 16 a modified form of the cutting mechanism is illustrated. In distinction from the arrangement previously described, a cutting knife 15 (lower knife) is actuated by the oscillating looper shaft 16 at the forward end 16a thereof. The entire cutting mechanism is connected with a mounting arm 17 and the latter held by a carrier arm 18 (Fig. 16). Thus the whole assembly represents a self-contained unit positioned underneath the supporting plate for the fabric.

10 At the shaft end 16a, a T-shaped groove 19 (Figs. 14 and 16) is provided for receiving a square head 20a of a pin 20 in various positions of adjustment corresponding to different throws of the knife. On this pin 20 a sleeve 21 is slid which can be held in any position of adjustment by means of a washer 22 and a nut 23. On the sleeve 21 is mounted for rotation a joint member 24 the forward end of which grips the lower end of a 15 knife carrier lever 25 in the manner of a fork and which is connected thereto by a bolt 24a. The sleeve 21 being carried by the looper shaft 16, shares in the oscillating and the axial movements thereof.

20 The knife carrier lever 25 is rotatably mounted on a pin 26 and carries at its upper end the lower knife 15 which is secured to the lever by a screw 27. An upper knife 28 is secured to the upper end of a lever 29 by a screw 30. The latter lever is mounted for rotation at 31 and urged with its 25 lower end on a regulating screw 33 by a spring 32. In this manner the upper knife 28 is resiliently arranged with respect to the lower knife 15.

25 In order to permit of providing a smaller or greater width for the overlapping margin of fabric respectively, the lower knife 15 is adjustably held in position by the eccentric pin 26 and the latter in turn is secured at 17 by a screw 34 (Figs. 9 and 14). The resiliently arranged upper knife 40 28 shares in these movements. The regulating screw 33 can be adjusted correspondingly to the desired cutting pressure to be exerted by the spring 32. The lower knife 15 is provided with a nose 15a (Fig. 15) which grips below the upper 45 knife and thereby causes the two knives to properly cooperate at all times.

50 Upon severing the fabric, during effecting the fastening seam, the fabric is advanced in adaptation to the shape of the feed channel 9 towards the throat 35 (Fig. 5) with which the front needle 36 (Figs. 3, 3b, and 4) cooperates. Fig. 4 shows the manner in which the left piece or web of fabric is pierced at the very edge thereof or near the same, whereas the right web is pierced substantially behind its edge. This figure also shows the needle 36 to assume a vertical position. The looper 42 is just starting to catch the loop formed in the needle thread.

55 Fig. 7 depicts a longitudinal section through the fastening seam along the line VII—VII in Fig. 4, the upper fabric layer shown in Fig. 7 to be considerably thicker representing the fabric which is pierced at the extreme edge only, whereas the lower much thinner fabric layer represents the fabric which is pierced as usual behind the edge. Thus, the web of fabric 7 is pierced only at its extreme edge and the web 8 pierced substantially behind the edge. The manner of interlacing the needle thread 37 with the looper thread 38 is also 60 evident from Fig. 7.

5 After the finishing of the fastening seam, the seam covering stitching is effected with the margin 39 extending horizontally (Fig. 6). This figure shows the two layers of fabric 7 and 8 to be pierced by the needles 40 and 41 respectively and the looper 47 to be just starting to catch the left needle thread loop, and on further advancing in the direction of the arrow to catch also the right needle thread loop (Figs. 6 and 3c). During the return movement of the looper 47, the looper shaft 10 10 is imparted an axial displacement towards the front, the webs of fabric 7 and 8 are pushed rearwardly by the feed dog 43, and the two needles 40 and 41 moved downwardly to pierce the webs of fabric 7, 8 and to project into the triangular loop of the looper thread (not shown). Thereby the marginal portion 39 along the suture is sewed down and the seam covering stitching performed. The manner in which the two needle threads 44 and 45 for the covering stitch and 20 the under-thread 46 interlace is evident from Fig. 8. Furthermore, the Fig. 8 shows the fastening seam 11 and the seam covering stitching 44, 45, 46 as seen from the upper and lower side (the upper side is shown to the left and the lower 25 side to the right).

25 A modified form of carrying out the combined fastening and seam covering stitching according to the invention is shown in the Figs. 2, 9, and 14. The Figs. 2 and 9 show the marginal portions of 30 the two pieces of fabric to be inserted in the feed channels 9 and 9a respectively in downwardly directed position. Fig. 10a illustrates the exact shape of the feed channel 9a of the needle plate 35 10b.

30 In connection with this example, Fig. 10a shows the three needles 48a, 48b, 48c to be aligned. Therefore, the three needles cooperate, as compared with the previously described example of the combined fastening and seam covering stitching, with only one looper 49 (Fig. 11), thus working with three needle threads and one under-thread. In Fig. 11 is indicated how the middle needle 48b pierces the extreme edge of the upper 40 web of fabric, whereas at the same time the left 45 needle 48a and the right needle 48c pierce both webs 7, 8 respectively substantially behind the edge. In Fig. 12, which illustrates a longitudinal section of the suture on the line XIII—XII in Fig. 11, it is evident that the upper web of fabric which 50 is shown to be considerably thicker, is the one pierced at the extreme edge, whereas the lower web, which is shown to be thinner, is pierced substantially behind the edge. Thus also here the web of fabric 7 is pierced only at the very edge and 55 the web 8 wholly behind the edge, by the same needle.

55 Before the piercing at the extreme end of an edge or wholly behind the edges is effected by the needles, the overlapping margin of the suture is 60 changed from a vertical disposition to a horizontal disposition in conformity to the shape of the feed channel 9a (Fig. 11). In this figure it is evident that the looper 49 is just starting to catch the loop formed in the thread of the needle 48a 65 and in keeping on moving in the direction of the arrow will also catch the loops in the threads of the middle needle 48b and the right needle 48c.

65 During the return movement of the looper 49, the looper shaft 16 is imparted an axial movement 70 towards the front and the webs of fabric 7 and 8 are pushed rearwardly by action of the feed dog 43, whereas the three needles 48a, 48b, 48c are caused to project into the triangular thread loop (not shown) on protruding through the webs 75 7.

- and 8. In this manner the marginal portion 39a of the suture is layed down flat and the seam covering stitching effected. The manner in which the threads of the three needles 50a, 50b, 50c for the seam covering stitch and the under-thread 51 interface is evident from Fig. 13. This figure also shows the seam covering stitching from the upper and lower sides (to the left the upper side and to the right the underside).
- 10 I do not limit myself to the particular size, shape, number or arrangement of parts as shown and described, all of which may be varied without going beyond the scope of my invention as shown, described and claimed.
- 15 What I claim is:
1. In a method of mechanically effecting combined fastening and seam covering stitches on fabrics to be sewed together, the steps of guiding the marginal fabric portions adjoining each other in a downwardly folded relation at any convenient angle to a common direction of stitching towards the position of sewing, trimming the edges of said downwardly folded marginal portions close up to the fabrics, piercing the folded marginal portion of the upper fabric at least at the extreme edge of said fold and the marginal portion of the lower fabric, for effecting the fastening stitching, and piercing both fabrics on either side of said fold, for effecting the stitching for covering the edges of said marginal portions on the underside of the flat seam.
  2. In a method of mechanically effecting combined fastening and seam covering stitches on fabrics to be sewed together, the steps of guiding the marginal fabric portions adjoining each other in a downwardly folded relation at any convenient angle to a common direction of stitching towards the position of sewing, trimming the edges of said downwardly folded marginal portions close up to the fabrics at equal lengths from the fold in the upper fabric, folding said marginal portions down flat onto the underside of the upper fabric, piercing the marginal portion of the upper fabric at least at the extreme edge of said fold and the marginal portion of the lower fabric, for effecting the fastening stitching, and simultaneously piercing both fabrics on either side of said fold, for effecting the stitching for covering the superposed edges of said marginal portions on the underside of said upper fabric.
  3. In a method of mechanically effecting combined fastening and seam covering stitches on fabrics to be sewed together, the steps of guiding the marginal fabric portions adjoining each other in a downwardly folded relation on the skew to a common direction of stitching towards the position of sewing, trimming the edges of said downwardly folded marginal portions close up to the fabrics at equal lengths from the fold in the upper fabric, piercing the marginal portion of the upper fabric at least at the extreme edge of said fold and the marginal portion of the lower fabric, for effecting the fastening stitching, folding said marginal portions down flat onto the underside of the upper fabric, and piercing both fabrics on either side of said fold, for effecting the stitching for covering the superposed edges of said marginal portions on the underside of said upper fabric.
  4. In a method of mechanically effecting a plural needle seam on fabrics to be sewed together, the steps of piercing with one needle two marginal fabric portions adjoining each other in a downwardly folded relation on the skew to a common direction of stitching and having been trimmed conjointly in positive parallelism with

said line of piercing at equal lengths from the fold in said upper fabric at least at the extreme edge of said fold for effecting the fastening stitching, folding said marginal portions down flat onto the underside of said upper fabric, and piercing both fabrics on either side of said fold for effecting the stitching for covering the superposed edges of said marginal portions on the underside of said upper fabric.

5. In a machine for effecting combined fastening and seam covering stitches on fabrics to be sewed together, in combination, a needle plate cooperating with three sewing needles reciprocating in a common direction of stitching, a means comprised by said needle plate adapted for guiding the marginal fabric portions adjoining each other in a downwardly folded relation at any convenient angle to said common direction of stitching towards said sewing needles, a cutting mechanism cooperating with said guide means ahead of said needles, for trimming the edges of said downwardly folded marginal portions close up to the fabrics, and actuating means for said needles adapting the same for piercing the folded marginal portion of the upper fabric at least at the extreme edge of said fold and the marginal portion of the lower fabric, for effecting the fastening stitching, and for piercing both fabrics on either side of said fold, for effecting the stitching for covering the edges of said marginal portions on the underside of the flat seam.

6. In a machine for effecting combined fastening and seam covering stitches on fabrics to be sewed together, in combination, a needle plate cooperating with three sewing needles reciprocating in a common direction of stitching, a guide means comprised by said needle plate, portions on said guide means for guiding the marginal fabric portions adjoining each other in a downwardly folded relation at any convenient angle to said common direction of stitching towards said sewing needles, a cutting mechanism cooperating with said guide means ahead of said needles from under said needle plate for trimming the edges of said downwardly folded marginal portions close up to the fabrics, an upper movably arranged knife and a lower fixed knife provided for said cutting mechanism, a fabric feed device operatively connected with said cutting mechanism and adapted for feeding said marginal fabric portions through said guide means, means for adjusting said cutting mechanism relatively to said needle plate and transversely to the direction of the seam as well as longitudinally thereof, and actuating means for said needles adapting the same for piercing the folded marginal portion of the upper fabric at least at the extreme edge of said fold and the marginal portion of the lower fabric, for effecting the fastening stitching and for piercing both fabrics on either side of said fold, for effecting the stitching for covering the edges of said marginal portions on the underside of the flat seam.

7. In a machine for effecting combined fastening and seam covering stitches on fabrics to be sewed together, in combination, a needle plate cooperating with three sewing needles reciprocating in a common direction of stitching, a guide means comprised by said needle plate adapted for guiding the marginal fabric portions adjoining each other in a downwardly folded relation at any convenient angle to said common direction of stitching towards said sewing needles, looper means cooperating with said needles, a cutting mechanism cooperating with said guide means

ahead of said needles and said looper means, a lower movably arranged knife and an upper resiliently arranged knife comprised by said cutting mechanism, means for adjusting said cutting mechanism for trimming the edges of said marginal fabric portions different lengths away from the fabrics, a fabric feed device operatively connected with said cutting mechanism and adapted for feeding said marginal fabric portions through said guide means, and actuating means for said needles adapting the same for piercing the folded marginal portion of the upper fabric at least at the extreme edge of said fold and the marginal portion of the lower fabric, for effecting the fastening stitching and for piercing both fabrics on either side of said fold, for effecting the stitching for covering the edges of said marginal portions on the underside of the flat seam.

8. In a machine for effecting combined fastening and seam covering stitches on fabrics to be sewed together, in combination, a needle plate cooperating with three sewing needles reciprocating in a common direction of stitching, a guide means comprised by said needle plate adapted for guiding the marginal fabric portions adjoining each other in a downwardly folded relation at any convenient angle to said common direction of stitching towards said sewing needles, looper means cooperating with said needles, a cutting mechanism cooperating with said guide means ahead of said needles and said looper means, a lower movably arranged knife and an upper resiliently arranged knife comprised by said cutting mechanism, means for adjusting said lower knife vertically for trimming the edges of said marginal fabric portions different lengths away from the fabrics, a fabric feed device operatively connected with said cutting mechanism and adapted for feeding said marginal fabric portions through said guide means, and actuating means for said needles adapting the same for piercing the fold-

ed marginal portion of the upper fabric at least at the extreme edge of said fold and the marginal portion of the lower fabric, for effecting the fastening stitching and for piercing both fabrics on either side of said fold, for effecting the stitching for covering the edges of said marginal portions on the underside of the flat seam. 5

9. In a machine for effecting combined fastening and seam covering stitches on fabrics to be sewed together, in combination, a fabric supporting plate, a needle plate cooperating with three sewing needles reciprocating in a common direction of stitching, a means in said needle plate adapted for guiding the marginal fabric portions adjoining each other in a downwardly 15 folded relation at any convenient angle to said common direction of stitching towards said sewing needles, looper means cooperating with said needles, a cutting mechanism in the form of a self-contained unit arranged underneath said 20 fabric supporting plate and cooperating with said guide means ahead of said needles and said looper means, a lower movably arranged knife and an upper resiliently arranged knife comprised by said cutting mechanism, means for adjusting 25 said lower knife vertically for trimming the edges of said marginal fabric portions different lengths away from the fabrics, a fabric feed device operatively connected with said cutting mechanism and adapted for feeding said marginal fabric portions 30 through said guide means, and actuating means for said needles adapting the same for piercing the folded marginal portion of the upper fabric at least at the extreme edge of said fold and the marginal portion of the lower fabric, for effecting the fastening stitching, and for piercing both fabrics on either side of said fold, for effecting 35 the stitching for covering the edges of said marginal portions on the underside of the flat seam. 40

ERNST BUCHER.
